UNITED STATES PATENT OFFICE.

ELI F. BURCH, OF LAUREL SPRINGS, NEW JERSEY.

METHOD OF DISTILLING PETROLEUM.

1,396,249.

Specification of Letters Patent.

Patented Nov. 8, 1921.

Application filed April 23, 1917. Serial No. 163,826.

To all whom it may concern:

Be it known that I, ELI F. BURCH, a citizen of the United States, residing at Laurel Springs, in the county of Camden and State of New Jersey, have invented certain new and useful Improvements in Methods of Distilling Petroleum, of which the following is a specification.

The principal object of my invention is to provide a new and improved method for distilling certain kinds of petroleum. Another object of my invention is to provide such a method that shall secure the lubricating oil content of the petroleum with as little diminution as possible due to conversion thereof into other components. Still another object of my invention is to provide an improvement in the art of distilling petroleum by which the proportion of lubricating oil obtained therefrom shall be maintained as high as practicable. All these objects and others will be better understood in connection with consideration of specific examples of my method. Accordingly, I now proceed in some detail to describe a specific embodiment of my invention, but it will be understood that this is only by way of example and that the scope of the invention is defined in the appended claims.

Referring to the drawings, Figure 1 is a side elevation of apparatus that may be used in practising my improved method;

Fig. 2 is a top plan view of the same, and Fig. 3 is a diagrammatic representation of apparatus that may be used in connection with this method.

Referring more particularly to Fig. 3, I fill the retort or still A about half full of Mexican petroleum, introducing it through the opening normally closed by the plug 21. A fire is made under the retort A and a gentle heat applied to drive off the lighter gases and vapors through the pipe 1 and through the condenser B. The vapors condense and run down through the look-box 22 into the tank C where they collect, but the more permanent gases are drawn from the box 22 through the suction pipe 4 to the pump D and discharged thence through the pipe 13 into the gas tank E. In the look-box 22 there is a window 23 through which the condensate from the condenser B can be observed. The gas in the tank E is subject to a pressure which may be regulated by the weights 24 and a part of this gas is discharged through the pipe 14 and valve 30

to the perforated pipe 16 under the petroleum level in the still A. This gas discharging through the perforations in the pipe 16 agitates the petroleum in the still A and facilitates in a marked degree the evolution of the oil vapors therefrom. Thermometers are provided at 24 and 25, so that the temperature of the liquid within the still A can be observed and also the temperature of the vapor as it leaves the still. After a sufficient quantity of gas has accumulated in the tank E, part of it can be taken to the burner 26 and used for heating the still. If more gas accumulates in the tank E than can be used in this way it can be diverted as desired through the branch pipe 27. Pressure gages are provided at 28 and 29. The gage 28 shows the pressure substantially on the suction side of the pump D and the gage 29 shows the pressure of the gas as it is delivered to the perforated pipe 16. In practice, I have found that it works well to have the pressure at the gage 28 about one pound below atmospheric pressure and the pressure at the gage 29 about four pounds above atmospheric pressure.

When the distilling process is commenced, of course the lighter oils or naphthas come off first for a given moderate temperature maintained in the still A. It is convenient after these have been practically all driven over to the tank C to make a "cut" and empty the contents of tank C and operate the still for a second stage at a higher temperature, driving off the intermediate fuel oils and collecting them in the tank C. After these have been practically all obtained it is convenient to make another "cut," and empty the tank C of its contents and operate at a still higher temperature to get the lubricating oils from the petroleum now remaining in the still A. The number of cuts to be made in this way during the distillation of a single batch of the petroleum is more or less an arbitrary matter and is simply for convenience in effecting the ultimate desired separation of the various oils in the petroleum. The important feature of my process is that by continuously pumping the gases back into the still through the perforated pipe 16, I can carry the process to a point where only coke will be left in the still A, and yet I can obtain the maximum proportion of lubricating oils from the petroleum.

Whether or not the cuts are made to sepa-

rate the lubricating oils in stages from the lighter oils, it is a comparatively easy matter according to well known methods to complete the refining of the lubricating oils 5 after they have been collected by condensation in the tank C.

If it were attempted to distil the Mexican petroleum merely by the application of heat and without the introduction of the gases 10 through the perforated pipe 16, as by completely closing the valve 30, the result would be that at the higher temperatures necessary for driving off the heavier lubricating oils, these oils would not be obtained in any 15 where near the same degree of purity as when the gas is introduced in accordance with the normal procedure of my method. In the absence of the gas introduced through the pipe 16, the application of heat to the 20 still at this later stage would apparently decompose the lubricating oils, breaking up their molecules, and giving a large proportion of fuel oil only a little heavier than kerosene and of much less value than the 25 lubricating oil. This is easily demonstrated experimentally, for when lubricating oils are being given off with say a temperature at the thermometer 24 of about 400° F. and with the gas flowing normally through the 30 pipe 16, if the gas flow is interrupted by closing down the valve 30, the supply of oil entering the tank C as viewed through the window 23 will stop, and no condensate will go over until the temperature has been raised 35 considerably, say to 500° F. Then, however, the condensate will be of entirely different character, not the comparatively heavy lubricating oil that was obtained before the valve 30 was closed, but lighter 40 oil, only slightly heavier than kerosene, the so-called fuel oil.

The Mexican oil with which I have found my improved method to be especially advantageous is a double base oil, that is it has 45 both paraffin and asphalt as its basic constituents. In attempting to distil it merely by the application of heat, the lightest ingredients are obtained without difficulty but as soon as the process progresses to the point 50 of raising the temperature to drive off the lubricating oils, they appear to be broken down and decomposed into lower members of the series, and these apparent decomposition products are principally fuel oils of 55 the least value of the various petroleum derivatives. Attempting to distil this Mexican oil by the mere application of heat actually gives lighter oils at the higher temperatures than were obtained by the moderate 60 temperatures preceding, apparently for the reason that at the higher temperatures there is such extensive decomposition as practically to degrade a large proportion of the heavier oils to the comparatively lighter 65 fuel oils.

I find that in every stage of my process there is enough permanent gas given off to maintain a sufficient supply through the pipe 16. Of course, this gas circulates around and around through the system and its quantity is increased by evolution from the petroleum in the still A so that it accumulates in the tank E and the excess can be used to maintain the fire under the still and for other purposes. 70

It is not indispensable to a realization of the advantages of my method that the condensate should be removed from the tank C in cuts. It may be collected there altogether until the residue in the still A is mere coke, 80 but this will be with the assurance that the mixture in the tank C has an undiminished proportion of the higher members of the series, namely, the valuable and desirable lubricating oils. Inasmuch as it would be 85 necessary, however, to redistil the contents of the tank C to separate the lighter oils from the lubricating oils, it is a matter of convenience to make this separation at the first, by cuts as described. The coke that 90 forms in the still A as a result of my process is very porous and easily broken up and removed. This is one of the advantages of my process, for without the introduction of the gas as described, the coke might be dense, 95 hard and difficult to remove.

I have described my improved method as a matter of practice rather than of theory. Actually it obtains from the petroleum a large proportion of the higher lubricating 100 ingredients, a much larger proportion than I have been able to obtain in any other way. Just why this is, I do not consider to be vital to practicing my invention. It is possible that the blowing in of the gas 105 through the perforated pipe 16 may produce some hydrogenation of the oils remaining in the petroleum, but the determination of such points of theory of operation is not necessary to a practical realization of the benefit of my invention. 110

Referring to Figs. 1 and 2 of the drawings, I have provided two condensers B and B' and it will be seen that the pipes and valves are so connected that I can either 115 take the distilled gases and vapors through one condenser B on the way to the tank C and the pump D, or I can take these gases and vapors through the two condensers B and B' in succession, collecting the condensates in the respective tanks C and C'. 120

As to certain of its subject matter, this application is a continuation of application Serial No. 103,930, filed June 6, 1916.

Having thus described my invention, I 125 declare that what I claim as new and desire to secure by Letters Patent, is:

The process of distilling petroleum oil of high asphaltic content comprising gently heating a charge of the petroleum in a still 130

to vaporize only the lightest constituents, condensing the light oils out of the evolved gases at a temperature not sufficiently low to condense all of the evolved gases, collecting the gases that are not condensed at the temperature of condensation, increasing the heating of the still and passing these non-condensed gases back through the heated petroleum, and condensing the vapors evolved and collecting the non-condensed gases and repassing these non-condensed gases through the petroleum in the still, and continuing the heating of the still with a rise in temperature at each step and the passing of the gases through it and the condensation of the distillates and the collection of the non-condensed gases until the desired distillates have been separated from the charge, so as to avoid cracking of the constituents of the petroleum and to obtain a greater yield of the more valuable products such as lubricating oils from a given quantity of petroleum base of high asphaltic content. 15 20
